UNITED STATES PATENT OFFICE.

HERMAN T. SUNDSTROM, OF HOUSTON, TEXAS.

LINOTYPE AND INTERTYPE.

1,294,192.

Specification of Letters Patent. Patented Feb. 11, 1919.

Application filed September 25, 1917. Serial No. 193,070.

To all whom it may concern.

Be it known that I, HERMAN T. SUNDSTROM, a citizen of the United States, residing at Houston, in the county of Harris and 5 State of Texas, have invented certain new and useful Improvements in Linotypes and Intertypes, of which the following is a specification.

This invention relates to new and useful 10 improvements in a safety attachment for linotypes.

The object of the invention is to provide an attachment of the character described, which will operate automatically to stop 15 the matrices in the intermediate channel, and before they reach the mold disk, in case they have been improperly assembled in the assembling elevator. In operating a linotype, the matrices are first assembled in the 20 assembling elevator and some of these matrices are capable of being assembled in two positions, that is, in upper or lower position. If the matrices are 14 point or smaller, they should be assembled in lower 25 position so as to aline with the mold disk when carried into position for casting. If they do not aline with said disk, the casting metal will not be projected directly against said matrices, and an imperfect casting will 30 result; and furthermore the heated metal will escape, causing what is known as "front overflow" or "front squirt."

It is the object of this invention to provide an attachment of the character described 35 which will automatically stop the matrices in the intermediate channel before they reach the molding disk, in case they have been assembled in the wrong position in the assembling elevator and when the 40 matrices have been so stopped, they can be then adjusted to lower position before they are sent on through the intermediate channel to the molding disk of the linotype.

With the above and other objects in view, 45 the invention has particular relation to certain novel features of construction, operation and arrangement of parts, an example of which is described in this specification and illustrated in the accompanying drawings, wherein;

Figure 1, shows a side elevation of the vise cap of a linotype, showing also the intermediate channel associated therewith.

Fig. 2, is a plan view thereof.

Fig. 3, is an end elevation, showing the safety attachment in locked position.

Fig. 4, is a fragmentary end view of the delivery channel showing the safety attachment in neutral position.

Fig. 5, shows an enlarged fragmentary 60 end view thereof, with the safety attachment in active position.

Fig. 6, shows an enlarged plan view of the first elevator, filling piece, showing also a fragmentary view of the safety attach- 65

Fig. 7, shows a fragmentary sectional view of the vise cap, showing the safety attachment in locked position, and

Fig. 8, is an enlarged view of the intermediate channel showing the spring and locking pin. 70

Referring now more particularly to the drawings wherein like numerals of reference designate similar parts in each of the figures, the numeral 1, indicates the first elevator filling piece, which is hinged to the top of the vise cap 2 by means of the hinge 3. These parts are common to linotypes. The matrices 4 are assembled in an as- 75 sembling elevator, the same being a well known part of the linotype and consequently not being shown in the drawings, and from this elevator they travel along the intermediate channel 13 on their way to the 80 mold disk. In case matrices of 14 points or less are assembled in upper position, in the assembling elevator, they will not aline with the mold disk and consequently, should be adjusted before they reach said disk, so 85 as to come in perfect alinement therewith. The vise cap 2 is provided with a groove 3' and extending laterally from the filling piece 1 is a U-shaped member 2' which rests in said groove when said filling piece is in 90 active position.

Secured to the vise cap 2 and opposite the exit end of the intermediate channel 13 is an upstanding brace 7'. The upper and lower ends of this brace have bearings, in which 100 the actuating rod 7 operates, the lower end of said rod being turned laterally and forming an arm 6, and the upper end thereof being formed into a curved finger 8. One of the channel rails of the intermediate chan- 105 nel 13 has a bearing 10', and also has a flat spring 9 secured thereto at one end, the other end of said spring carrying the pin 10 which projects into said bearing 10', but normally does not project beyond the inner 110 surface of said channel rail. When the filling piece 1 is thrown into active position,

the U-shaped member 2' rests against the arm 6, causing a partial rotation of the rod 7, and carrying the free end of the finger 8 against the free end of the spring 9, forcing the pin 10 inwardly and projecting it into the intermediate channel in position so that it will engage against the matrices passing therethrough, in case they are assembled in upper position, as shown in Fig. 5, and thus locking said matrices against forward movement until they have been adjusted by the operator to lower position, and when so adjusted, to lower position, as shown by dotted lines in Fig. 2, they will then be free to pass on to the molding disk, and will align therewith, and form a perfect casting.

The intermediate channel has a front rail 14 and a back rail 15, provided with the lower and upper grooves 16, 19, and 17, 18, respectively, adapted to receive the corresponding lugs of the matrices, and to permit said matrices to occupy the upper and lower positions therein.

When the filling piece 1 is thrown out of active position, as shown by dotted lines in Fig. 1, the arm 6 is released and the flexibility of the spring 9 withdraws the pin 10 from locking position in the intermediate channel 13.

30 What I claim is:

1. In a device of the character described, the combination with a channel, provided for the passage of the matrices, of a locking mechanism, adapted to be projected into said

channel in front of said matrices, and a filling piece which actuates said locking mechanism when in active position.

2. In a device of the character described, the combination with a channel along which matrices travel to the molding disk, of a locking means adapted to be projected into said channel, a yieldable member normally holding said means withdrawn from the channel, an actuating mechanism, and a filling piece operating through said mechanism, when in active position, to hold said means projected into said channel, in path of said matrices.

3. In a device of the character described, the combination with a channel, along which matrices travel to a molding disk, of a filling piece, an actuating mechanism, a locking means, a member connected to said locking means and normally holding the same withdrawn from the channel, said actuating mechanism being actuated by the filling piece when in active position and operating against said member to hold said means projected into the channel in front of the matrices, and locking them against movement along said channel.

In testimony whereof I have signed my name to this specification in the presence of two subscribing witnesses.

HERMAN T. SUNDSTROM.
